COMBINED MOUNTING BRACKET AND ENCLOSED DRIVE AND CONTROL UNIT FOR A PANNING CAMERA

Gerald E. Kardach, South Milwaukee, Wis., assignor to Videosonics, Inc., Milwaukee, Wis.

Filed May 11, 1972, Ser. No. 252,535

Term of patent 14 years

Int. Cl. D16—05

U.S. Cl. D61—1 G

The figure is a top front and right side perspective view of a combined mounting bracket and enclosed drive and control unit for a panning camera showing my new design; the left side being mirror image thereto and the bottom, and bracket end being plain and unornamented.

I claim:

The ornamental design for a combined mounting bracket and enclosed drive and control unit for a panning camera, as shown and described.
